DEWEY L. HAYES, OF ROSSVILLE, GEORGIA, ASSIGNOR, BY MESNE ASSIGNMENTS, TO EVERLASTICK VARNISH, INC., OF CHATTANOOGA, TENNESSEE, A CORPORATION OF TENNESSEE

ROLL FOR SPINNING MACHINES AND METHOD AND COMPOSITION FOR PRODUCING THE SAME

Application filed November 7, 1930. Serial No. 494,125.

This invention relates to improvements in rolls for spinning machines and method and composition for producing the same.

A well known and widely used type of drafting roll is the leather-covered roll. The leather covering for drafting rolls has important advantages and is very desirable, but the leather-covered roll does not well withstand wear; after a limited period of service, the outer face of the leather covering becomes rough and the roll unfit for further use, and according to the present practice, the worn rolls must be returned to the factory to be provided with new coverings.

Objects of the present invention are to provide an improved drafting roll, to provide an improved covering for such rolls that will be of an efficient nature and capable of resisting wear to a high degree, to provide an improved composition to be applied to the roll covering that will preserve and protect the same against wear, and to provide a method whereby the roughened surfaces of worn roll coverings can be readily restored or reconditioned for further use.

The invention with other objects and advantages thereof will be understood from the hereinafter contained detailed description when considered in connection with the accompanying drawings forming part hereof and illustrating drafting rolls constructed in accordance with the teachings of the invention.

In the drawings:

Figure 1 is an elevation of a roll constructed in accordance with the present invention;

Figure 2 is a transverse section;

Figure 3 is an elevation of a drafting roll with the leather covering worn and roughened on its outer surface.

Figure 4 is a transverse section of the roll illustrated in Figure 3.

Figure 5 is a transverse section of a roll with a worn leather covering after the covering has been treated to recondition the same.

In Figures 1 and 2 of the drawings is illustrated a roll comprising a core 1, a fiber filling 2, and an outer covering 3 of sheepskin, the construction so far described being a conventional form of drafting roll.

In accordance with the present invention, a composition coating is applied to the outer face of the leather covering 3. The composition is applied to the roll in the form of a solution consisting of a mixture of ribbon glue, acetic acid, oil of origanum, wood alcohol, powdered soapstone and water. The following is an example of the proportions in which the different ingredients are employed in the composition. To prepare one gallon of the solution, take three pounds of ribbon glue and thoroughly beat up and dissolve the same with one half gallon of acetic acid No. 8. Then add two ounces of oil of origanum, one pint of wood alcohol, two full tablespoons of powdered soapstone and one pint of water. Instead of using ribbon glue as a filler and binder, other proteins having like qualities may be employed, and in place of oil or origanum, which acts as a drier and preservative, other oils having like properties may be used.

The wood alcohol acts as a filler and drying agent. The powdered soapstone acts as a filler and is effective in producing a slick protective wearing surface on the roll so that the yarn and yarn ends will not stick thereto.

The solution is applied by rubbing the same over the surface of the roll and particularly satisfactory results have been obtained by employing rubber gloves and dipping the gloved hand into the solution and rubbing over the surface of the roll. After application of the solution, the roll is placed in a rack to dry, and, after from one to three hours, is ready for use.

A leather covered roll provided with the composition coating as hereinbefore set forth will resist wear much better than the ordinary construction of roll equipped with a plain leather covering, and has proven highly satisfactory in use. The resulting roll surface will not become wet or sticky and the yarn will not adhere to it.

The invention also comprehends the treatment of rolls having old worn coverings, which would ordinarily be discarded, to restore or recondition the same for further use. In Figures 3 and 4 of the drawings, I have shown an old or worn roll, and in Figure 5

is illustrated the old roll after the same has been reconditioned. In accordance with the teachings of the invention, a coating of the composition hereinbefore described is applied to the worn roughened face 4 of the used roll and the same is allowed to dry from fifteen to twenty minutes. Next the roll is smoothed off as by the use of an emery cloth and a second coating of the solution applied.

10 The roll is then allowed to dry and is ready for use in from one to three hours.

The improved roll produced in accordance with the present invention possesses important advantages. It will resist wear much better and remain serviceable for a much longer period than the ordinary construction of roll provided with a plain leather covering. As will be appreciated, an important feature of the invention resides in the method 15 of reconditioning worn rolls, the same providing for readily reconditioning the worn roughened coverings, which in present practice are discarded. The rolls may be reconditioned a number of times and the invention thus provides for a considerable reduction 20 in the expense incident to the use of drafting rolls.

What I claim is:

1. A drafting roll for spinning machines, provided with a covering of leather coated on its outer face with a composition including glue, an acid for dissolving the glue, a drying agent, and powdered soapstone.
2. A drafting roll for spinning machines, provided with a covering of leather coated on its outer face with a composition consisting of a mixture of glue, an acid for dissolving the glue, a drying oil, alcohol, and powdered soapstone.
3. A drafting roll for spinning machines, provided with a covering of leather coated on its outer face with a composition consisting of a mixture of glue, acetic acid, oil of origanum, wood alcohol, and powdered soapstone.
4. A drafting roll for spinning machines, provided with a covering of sheepskin coated on its outer face with a composition including glue, an acid for dissolving the glue, a drying agent, and powdered soapstone.
5. A drafting roll for spinning machines, provided with a covering of soft flexible material coated on its outer face with a composition including glue, an acid for dissolving the glue, a drying agent, and powdered soapstone.
6. The method of treating roughened worn leather coverings of drafting rolls to recondition the same for service, including the steps of smoothing off the outer face of the covering, and applying to the worn face of the covering a solution including glue, an acid for dissolving the glue, a drying agent, and powdered soapstone, and permitting the covering to dry.

7. The method of treating roughened worn leather coverings of drafting rolls to recondition the same for service, consisting in first applying to the worn outer face of the leather covering a solution including glue, an acid for dissolving the glue, a drying agent, and powdered soapstone, permitting the covering to dry, next smoothing off the outer face of the covering with emery cloth, and then making another application of said solution to the worn face of the covering, and permitting the same to dry.

8. The method of treating roughened worn leather coverings of drafting rolls for spinning machines to recondition the same for service, consisting in rubbing on the outer face of the roll a solution including glue, an acid, a drying agent, and powdered soapstone, permitting the covering to dry, next smoothing off the outer face of the covering, then making another application of said solution to the covering by rubbing the solution thereon, and permitting the covering to dry.

9. A liquid composition for treating the coverings of drafting rolls for spinning machines, said composition including glue, a solvent for the glue, a drying agent, and powdered soapstone.

10. A liquid composition for coating the coverings of drafting rolls for spinning machines, said composition including glue, an acid for dissolving the glue, a drying oil, and powdered soapstone.

11. A liquid composition for coating the coverings of drafting rolls for spinning machines, said composition consisting of a mixture of glue, an acid for dissolving the glue, a drying oil, alcohol, and powdered soapstone.

12. A liquid composition for coating the coverings of drafting rolls for spinning machines, said composition consisting of a mixture of glue, acetic acid, oil of origanum, wood alcohol, and powdered soapstone.

In testimony whereof I hereunto affix my signature.

DEWEY L. HAYES.
